CLAIM

The ornamental design for a motorcycle passenger backrest, as shown and described.

DESCRIPTION

FIG. 1 is a front, left, and top perspective view of a motorcycle passenger backrest, showing my new design; FIG. 2 is a rear, right, and bottom perspective view thereof; FIG. 3 is a front elevational view thereof; FIG. 4 is a rear elevational view thereof; FIG. 5 is a left side elevation view thereof; FIG. 6 is a right side elevation view thereof; FIG. 7 is a top plan view thereof; and, FIG. 8 is a bottom plan view thereof.

The broken lines depict portions of the motorcycle passenger backrest that form no part of the claimed design.
